MERCURY SWITCH FOR CONTROL
COMPASSESCarleton H. Bolin, Seattle, Wash.; Jessie R. Bolin
executrix of said Carleton H. Bolin, deceased

Application November 18, 1946, Serial No. 710,535

1 Claim. (Cl. 200—152)

1

This invention relates to compass controlled systems and circuits and more particularly to improvements in control compasses designed for use in connection with electrical systems, for example, systems of that character used for the automatic steering of ships as disclosed in my co-pending application filed on July 19, 1945, under Serial No. 605,992, wherein a ship's rudder is controlled in its steering function by a powered mechanism which, in turn, is controlled through electrical devices to which current is supplied under control of a compass.

It is the principal object of this invention to provide improved means whereby electrical current may be supplied under compass control for the energization of electrically operated devices.

More specifically stated, the object of the present invention is to provide novel and practical means adapted to be used in combination with the cover plate and compass card of a compass for making and breaking an electric circuit incident to oscillating action of the cover plate relative to the compass card.

It is also an object of the invention to provide circuit contacts of novel kind for use in control compasses of the kind above stated, that will minimize to the utmost degree any influence on the compass card in making or breaking a contact.

Still further objects of my invention reside in the details of construction of a mercury contact element and a contactor therefor, and in their relationship and mode of use as will hereinafter be fully described.

In accomplishing these and other objects of the invention, I have provided the improved details of construction, the preferred forms of which are illustrated in the accompanying drawings, wherein:

Fig. 1 is a plan view of a compass of typical form as equipped with contacts and contact actuating means in accordance with the present invention.

Fig. 2 is a horizontal, sectional view of the same.

Fig. 3 is an enlarged sectional view of the mercury contact members characterized by this invention.

Fig. 4 is a cross-section taken on line 4—4 in Fig. 3.

Fig. 5 is a plan view of a compass with an alternative form of contact mounting means.

Fig. 6 is an elevational view of parts, showing the relationship of the contacts to each other and

to the actuator cam fixed on the pivot bearing of the compass card.

Fig. 7 is a diagrammatic illustration of a control system with which the present compass controlled contacts are used.

For a better understanding of the mode of operation and use of the present compass control system and the novel contacts, it will here be explained that one use to which these parts may be applied would be that of the pilot compass and system disclosed in my co-pending application, previously mentioned, wherein I have described an automatic steering system for rudder equipped water craft. In accordance with the disclosures of that application, the ship's rudder is continuously oscillated in a comparatively short arc of travel by a reversible power means operating under control of the pilot compass; the compass, in turn, being oscillated in accordance with the rudder action, and by the rudder through circuit contacts carried on the compass card and plate that are engaged and disengaged by said relative movements, to effect the alternate energization and de-energization of an electrical control unit for the power device to reversely actuate the latter and thus to impart the oscillating motion to the rudder.

One of the special requirements for most satisfactory use of the present type of compass control system is that the functional engaging and disengaging of the circuit contacts shall not have any particular effect on compass card action and that the action of the compass shall not impair the utility of the delicate contact control members; therefore it is in respect to these requirements that the present improvements have been particularly directed.

Referring first to Fig. 7 in which I have, for purpose of better explaining the use and mode of operation of the compass, diagrammatically illustrated certain electrical devices as assembled in a control system for which a compass equipped with the present invention is adapted to be used, 10 designates, in its entirety, a control compass; 11 a relay and 12 a battery or other suitable source of electricity. Leading from opposite poles of the battery 12 are wires 13 and 14, the wire 13 leading to one side of the relay coil and the wire 14 to a binding post 15 which is mounted on the compass cover plate as shown in Fig. 1 or 5. Also, there is a circuit wire 16 leading from the other side of the relay coil to a binding post 17 mounted on the compass cover plate. The electrical contacts which are featured in this invention are supported by the two binding posts

3
 15 and 17 for adjustment thereby, and are electrically joined thereto, and these contacts are designated in Fig. 7, generally, by the reference numerals 19 and 20 and, as will presently be more fully explained, are adapted to be moved relative to each other to make and break a relay circuit by means on the compass card.

The making and breaking of the relay circuit, by the engaging and disengaging of the contacts 19 and 20, is for the purpose of energizing a solenoid for the actuation of a reversing switch 22 which controls the operation of electrical devices not herein shown or described, whereby the oscillatory action of the ship's rudder is effected.

As here shown, the switch 22 comprises a mercury tube 23 fixed on one end of a horizontally directed, vertically oscillating lever 24. The lever is pivoted between its ends on a support 25 and at its other end is operatively connected as at 26 with the armature 27 of a solenoid which is designated in its entirety by numeral 28. The solenoid has one terminal connected to a battery 30 or other suitable source of electricity, by a circuit wire 31 and a wire 32 connects the other pole of the battery with a contact 34 of the relay 11. Also, a wire 35 leads from the other terminal of the solenoid to the relay armature 36 which is adapted to make and break contact with the contact member 34, thus to energize or de-energize the solenoid. Upon the solenoid being energized, the lever 24 will be moved to reverse the position of switch 22.

Through the above described arrangement of parts, it will be understood that a current of very small value, for example of the order of .003 ampere, can be utilized to control the relay 11, and this may be utilized to control a solenoid circuit of much greater value, and this in turn to actuate the reversing switch. However, the contacts 19 and 20 for controlling the first of these circuits must be of such kind as not to require any appreciable effort on the part of the compass to bring them into and from circuit controlling contact. These contacts will be described more particularly with reference to the showing of parts in Figs. 1 to 4.

In Figs. 1 and 2, 59 designates the housing of a typical form of compass, having a glass cover plate 51 mounted thereon in suitable manner. The compass card is designated at 52 and is supported by a pivot stud 53 that is fixed vertically in the housing. As noted in Fig. 2, the pivot stud extends into the jewel case 54, or pivot housing, which is fixed to and extends upwardly from the card at its axial center.

In Fig. 1 it is shown that the binding posts 15 and 17, previously mentioned, extend through the cover plate substantially at diametrically opposite sides, and at their upper ends these posts are connected respectively to the circuit wires 14 and 16.

At its lower end, the post 15 has a flat head portion 60 and soldered thereto is a very fine circuit wire 61 that extends from the post 15 over the top of card 52, close to and slightly beyond the jewel case 54, as best shown in Fig. 2. Likewise, the binding post 17 has a flattened head portion 65 at its inner end to which one end of a wire 66 is soldered, and which wire, at its other end is soldered to the top portion of a small horizontally disposed barrel 68 formed from an electrically conductive metal and having an axial bore 69 therein of small diameter containing a quantity of mercury designated in Fig. 3 by numeral 70.

4
 5 At one end, the bore 69 is closed, but at its other end it is counterbored as at 71 and is fitted with a fiber closure plug 72 which has an axial bore 73 therethrough which is designed to freely contain therein, as noted in Fig. 3, and end portion 61' of the wire 61; this end portion being bent at a right angle to the wire.

The mercury containing barrel 68 is so supported that the end portion 61' of the wire 61 may be moved endwise in the bore 73 and thus brought directly into and from contact with the mercury 70. This relative movement of the wire 61' and barrel is here accomplished by means of 10 a cam member 89, or arm that extends radially from the side of the jewel case 54 of the compass card, and in such relationship to the wire 61 that by the oscillating of the compass housing through a predetermined arc, the cam will be engaged with the wire and so move it, with each reversal 15 in direction of oscillation, to break the circuit connection between the mercury 70 and part 61'.

For an exact determination of the position of the barrel, so that the end portion 61' of wire may at all times be axially centered in the passage 17, I provide a second support for the barrel. This comprises a post or screw 90 that is fixed 20 in the cover plate at about a 90° interval relative to the post 17 and this has a wire 91 fixed at one end to the post head and soldered at its other 25 end to the barrel as at 92 in Fig. 3.

The wires 66 and 91 each are formed with a right angle bend and loop, to give certain flexibility of movement thereto, and it is thus possible, by making rotative adjustment of the supporting 30 posts 17 and 90, to make those necessary slight movements of the barrel with exactness and also to shift it endwise to an extent sufficient to make whatever adjustments between mercury and wire 61' that are necessary.

40 To impart a better understanding of the nature of the invention, it will here be mentioned that in installations now made, the wire 61 has a diameter of .005" and the hole 73 has a diameter of .040, and a good circuit connection is made by merely contacting the inner end of wire 61' with the mercury 70.

The design of the metal barrel, preferably of bronze, and mercury chamber or bore 69 is such that the mercury is held in place in the bore 69 by induced capillary action and retained 50 against loss by the plug 72, which acts also as a guide for the wire 61', keeping it centrally located in bore 69. The mercury, in this instance, is made to adhere to the bore 68 of the barrel with capillary action by first washing the walls 55 of the bore with nitric acid.

In the alternative form illustrated in Figs. 5 and 6, the mercury containing barrel 68a is supported from post 17 by a straight length of 60 wire 95 and the contact wire 61a, which corresponds to wire 61 of the device of Fig. 1, is formed in a U-shaped bend. It is secured at one end to the post 15 and its loop portion extends beyond the center of the compass card, with its other leg portion passing adjacent the jewel case 54 for actuation by the arm 81 which extends radially from the jewel case in the same manner as previously explained in connection with the actuation of contact wire 61.

70 At its free end, the wire 61a has a contact portion 61b turned at right angle for entering the barrel 68a which is constructed like the barrel 68 in Fig. 3, and circuit contact is made between the mercury therein and wire 61b in a 75 manner as previously explained.

Having thus described my invention, what I claim as new therein and desire to secure by Letters Patent is:

In combination, a rotary movable cam element, an electric circuit and contact elements connected therein for controlling flow of current in the said circuit; one of said contact elements comprising a body of electrically conductive metal formed with a capillary bore open at one end, a mercury column retained in the said bore by capillary attraction and the other of said contact elements comprising a resilient circuit wire of substantial length fixed at one end engaged and flexed by said cam in its rotating action and having its opposite end portion turned at a right angle and extended directly into the open end of said bore into circuit closing contact with the said mercury column; said cam being arranged to contact said resilient wire for moving the said end portion of the wire from contact with the mercury column; said bore of the mercury containing body being counterbored

at its open end, a closure plug fitted in the outer portion of the counterbore leaving its inner portion open as a reservoir for mercury spilled from the bore, and having a small diameter bore therethrough through which the end portion of the wire extends with clearance for its functional movements.
